CLAIM

The ornamental design for an apparatus for adhering ring protectors to punch holes on paper, as shown.

DESCRIPTION

FIG. 1 is a front elevational view of an apparatus for adhering ring protectors to punch holes on paper showing my new design;

FIG. 2 is a rear elevational view thereof;

FIG. 3 is a left side view thereof;

FIG. 4 is a right side view thereof;

FIG. 5 is a top plan view thereof; and,

FIG. 6 is a bottom plan view thereof.

The broken lines shown in the drawings are included for the purpose of illustrating environment and form no part of the claimed design.
